Primary Examiner — Cynthia M Chin

(74) Attorney, Agent, or Firm — Payam Moradian

(57) **CLAIM**

I claim the ornamental design for a skate tool, as shown and described.

DESCRIPTION

FIG. 1 is a perspective view of a first embodiment of a skate tool;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1 to 7 illustrate portions of the skate tool that form no part of the claimed design.
